UNITED STATES PATENT OFFICE.

GEORGE A. HATTERSLEY, OF NORWOOD, AND GUSTAVE A. STRUB, OF TOLEDO, OHIO,
ASSIGNORS TO SAID GEORGE A. HATTERSLEY, AND WILL C. HATTERSLEY AND
DAVID E. HUNT, BOTH OF CINCINNATI, OHIO, AND ELIJAH B. CORNELL, OF PHILA-
DELPHIA, PENNSYLVANIA.

METALLIC WHEEL.

1,161,810.

Specification of Letters Patent. Patented Nov. 23, 1915.

Application filed February 7, 1914. Serial No. 817,126.

To all whom it may concern:

Be it known that we, GEORGE A. HATTERSLEY and GUSTAVE A. STRUB, the first residing at Norwood, Hamilton county, and the other at Toledo, Lucas county, both in the State of Ohio, have invented certain new and useful Improvements in Metallic Wheels, of which the following is a clear, full, and exact description, attention being called to the drawing which accompanies this application and forms a part thereof.

This invention concerns the construction of wheels which have metallic fellys and are intended for use in connections where lightness without impairment of strength and durability of construction is the desideratum.

Our invention consists of the construction of such a spoke as an article of manufacture and concerns also the means whereby its outer end is connected to the felly.

In the following specification and claim is found a full description of our invention, also of its parts and construction which latter is illustrated in the accompanying drawing, in which—

Figure 1 shows in elevation with parts broken out, a wheel provided with spokes constructed and connected in conformity with our invention. Fig. 2. is an axial section of the same, shown on an enlarged scale. Fig. 3. is a cross-section of the felly, showing manner of connecting the outer spoke-ends. Fig. 4. shows formation of the outer spoke end.

In the drawing, reference character A, indicates the outer, annular member of the wheel.

B indicates the hub, and C are a number of spokes attached at their ends to parts A and B and connecting them to each other. The annular member or felly is shown as constructed in a manner rendering it suitable for use in connection with our spoke. It is substantially of rectangular profile and made up of two annular parts, bent to the shape required, which is of a form resembling channel-rails. There is an inner and an outer one of these parts, they being interfitting and in engagement with each other at their parallel sides. Reference characters 7—7 indicate the parallel sides of the inner part and 8—8 indicate the parallel sides of the outer part. As to width these

sides, considered in a radial direction, may be alike or nearly so. By preference the width of the sides of the outer part is considerably less, and about as shown. The preferable material of these felly parts is pressed or rolled steel.

The spokes C, consist of the part 11, made of steel tubing and are connected at their outer ends to the inner side or web 12 of the inner part of the felly. At their inner ends they have four-sided, wedge-shaped shanks e made of cast-steel or drop-forged and connected to the steel-tubing by means of a metallic joint, that is brazed or welded. Two of the opposite sides of these shanks are so disposed as to render these shanks voussoir-shaped with reference to each other that is to say, when the spokes at their outer ends are connected to the felly, the sides of the shanks on adjoining sides of the spokes meet and assemble in hub-forming juxtaposition, leaving also a central circular opening b to admit the axle journal and such parts of a bearing for the same, as it may be desirable to use in any particular case.

Beyond connecting these shanks in a manner to hold them in hub forming alignment and to prevent their lateral displacement with reference to the plane of the wheel, or to render such connection possible, our invention does not concern any particular means which may be used for this purpose. This is because such means also involve the axle bearing which latter depends on the size of the axle journal. If ball-bearings are used, conditions change again. For these reasons, we merely provide for the possibility of connecting hub flanges 13—13 to each side of the wheel, said flanges being held to each other and to the spoke shanks between them by means of bolts 14. As to the spoke shanks, the openings 15 for these bolts may be provided in various ways. As shown in Figs. 1 and 2, these openings 15 may be provided in the parallel sides 16 of the shanks. It is desirable however, in order to reduce weight, to omit these flat sides and leave the shanks open thereat. Openings to provide for the reception of the bolts are obtained.

At their outer ends the spokes are provided with shoulders 19 which contact with web 12 of the inner felly part. Beyond these

shoulders are necks 21 which are fitted into openings provided for them in said web. These necks extend beyond said web and terminate within the hollow space of the 5 felly where an additional shoulder 22 is provided on each neck which engages the side of the web within the felly.

In order to render possible the use of thin steel-tubing which does not present sufficient 10 thickness to permit formation of the shoulders, we use a thimble 23 as shown in Fig. 4, which is seated in the outer end of the spoke and connected thereto by a metallic joint, that is by brazing or welding. Beyond the 15 end of the spoke, the thickness of the wall of the thimble is enlarged outwardly to form a shoulder whereby it is seated against the end of the spoke. Beyond this shoulder the thickness of the wall of the thimble is 20 again reduced, the reduction being on the outside, to form the shoulder 19 which seats against the web of the felly. The part beyond this shoulder forms neck 21 which projects through the opening in the felly as 25 shown in Fig. 3, and is of sufficient length to provide the metal necessary for turning over to form shoulder 22, whereby the spoke is clenched to the felly, as shown in Figs. 1 and 2.

Having described our invention, we claim 30 as new:

In a wheel, a metallic spoke made of steel-tubing of limited thickness and having a reinforcing thimble seated in its outer end and connected with a metallic joint, the wall of 35 said thimble being outwardly enlarged between its ends to form a shoulder between the end of the spoke and the web of the felly, the portion of the thimble beyond said shoulder extending through an opening in 40 the web of the wheel felly and, being turned over and clenched against the side of said web and within the felly and around said opening, forming an additional shoulder whereby spoke and felly are connected to 45 each other.

In testimony whereof, we hereunto affix our signatures in the presence of two witnesses.

GEORGE A. HATTERSLEY.
GUSTAVE A. STRUB.
